(57) **CLAIM**

The ornamental design for a bait station, as shown and described.

DESCRIPTION

In a preferred embodiment the nature of this product is as a device for attracting and killing crawling insects.

FIG. 1 is a left, top, frontal perspective view of a bait station embodying our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a left, top, frontal perspective view of a second embodiment that is identical to the first embodiment but for the upper cover being transparent and certain internal structures being somewhat visible as a result thereof;

FIG. 9 is a front elevational view thereof;

FIG. 10 is a rear elevational view thereof;

FIG. 11 is a left side elevational view thereof;

FIG. 12 is a right side elevational view thereof;

FIG. 13 is a top plan view thereof; and,

FIG. 14 is a bottom plan view thereof.

The broken line representations of the bottom structure in FIGS. 7 and 14 are for purposes of illustration only and form no part of the claim.
